Attorneys

UNITED STATES PATENT OFFICE.

CHARLES W. KIRSCH, OF STURGIS, MICHIGAN.

CURTAIN ROD.

Application filed January 29, 1920. Serial No. 354,816.

To all whom it may concern:

Be it known that I, CHARLES W. KIRSCH, citizen of the United States, residing at Sturgis, in the county of St. Joseph and State of Michigan, have invented certain new and useful Improvements in Curtain Rods; and I do hereby declare the following to be a full, clear, and exact description of the invention, such as will enable others skilled in the art to which it appertains to make and use the same.

This invention has for its object to provide an improved curtain rod and more particularly to provide a curtain rod consisting of two equal opposed parts pivotally mounted on opposite sides of a window frame, each of which is adapted to have a curtain or drape suspended therefrom to be normally positioned substantially parallel with the window sashes and to be swung outwardly upon opening the window or when it is desired to clean the same so as to be out of the path of draughts of air entering or leaving the windows and to prevent soiling of the curtains or drapes while washing the windows.

The present invention relates more particularly to means for latching or firmly holding the curtain rods in normal position while permitting ready movement thereof to their outward position without placing any considerable strain upon the curtains or drapes suspended from the rod and by means of which it is adapted to be operated.

The invention consists in features of construction and combinations of parts hereinafter fully described and particularly claimed.

In the accompanying drawings illustrating suitable embodiments of the invention:

Figure 1 is a fragmentary view front elevation of a window frame equipped with a pair of curtain rods constructed in accordance with the invention.

Figure 2 is a fragmentary top plan view of the window frame and curtain rods mounted thereon.

Figure 3 is a perspective view of one of the end members of the curtain rod and a bracket in which it is pivotally mounted.

Figure 4 is a plan section on the line 4—4 of Figure 1 showing the rod and bracket detached from the window frame.

Figures 5 and 6 are sectional views similar to Figure 4 showing modified forms of construction.

Each of the members of the complete curtain rod comprises the bracket A consisting of a plate of sheet metal having a plurality of projections B provided with openings 60 for the passage of nails or screws for securing said plate to the window frame or the like, and which is also equipped with a pair of opposed parallel flanges C in the outer ends of which a pivot pin D is 65 mounted.

Suitably secured to the plate A is a flat spring E, the body portion of which lies flat upon said plate. One end of said spring E is bent to project outwardly from the 70 plate A and provides an ogee curved formation or tongue F which is very flexible and is adapted to engage the curved end portion G of the flange H integral which is with the curtain rod member I. The latter is formed 75 of sheet metal and presents a flat outer face or web having overturned side flanges J and being C-shaped in the cross-section as shown in Figure 3. The said member I is provided with two arms extending substantially at 80 right angles to each other, the outer arm K being adapted to telescopically receive an extension member L such as is shown in Figures 1 and 2.

The outer or free end portion of the 85 tongue F of the spring E is normally positioned near the pivot pin D than the outermost convex face of the projection G of the flange H of the rod so that as the rod is turned in one direction to the position 90 shown in Figures 1 to 4 inclusive, the said convex face of the tongue G will be sprung past the outer end portion of the tongue F. The free end portion of the latter will then bear upon the free end portion of the tongue 95 G to retain the flange H and rod member I firmly in position shown in said Figures 1 to 4. When it is desired to turn the rod from the positions shown in said figures so that the extension member L and arm K 100 will extend substantially perpendicularly to the window frame or the plane of the plate A, the curtain or drape suspended from the rod will be drawn back and tension imparted to the extension member L to overcome the 105 resistance of the tongue F of the spring to the passage of the tongue G of the flange whereupon the rod will readily turn to the desired position and will be easily returned to its normal position in the same manner.

While I have shown the preferred construction embodying the invention in Fig-

ures 1 to 4 inclusive, such construction may be variously modified and suitable exemplary modifications are illustrated in Figures 5 and 6 respectively.

5 In Figure 5 it will be noted that the rod member I is devoid of the flange H and tongue G and that it terminates at a point spaced from the plate A. The latter carries a flat spring M which is bent to provide a curved stop formation N against which the web of the inner end of the rod member lying between the pivot pin D and plate A normally abuts. The curved portion N is continued in a double ogee curved 10 formation which provides a convex shoulder O over which the inner end of the member I must be sprung in turning the rod to and from the position shown in Figure 5 in an obvious manner. The extreme free 15 end portion P of said spring normally bears upon plate A and will move slightly longitudinally along the same as the convex portion O is depressed or forced toward the plate A under the influence of the pressure 20 exerted thereon by the passage of the end of the rod member I over the same.

In Figure 6, the plate A is shown as provided at one end with an ogee curved tongue or flange Q projecting outwardly from the 25 outer face of the plate A and extending substantially perpendicularly to the flanges C. The said tongue or flange Q presents an outer convex face R over which the ogee curved free end portion S of the spring T 30 which is riveted or otherwise rigidly secured to the flange U, corresponding to the flange H shown in Figures 3 and 4, is adapted to

be sprung as the rod is moved to and from the position shown in Figure 6. The said spring T is substantially tubular in form, so 40 that the flange Q moves into and out of the same through an open-mouth portion formed between the portion S thereof and the opposed portion V contiguous to the part of the spring secured to and lying upon 45 the flange U.

The operation of the rod shown in Figure 6 is identical with that shown in the remaining figures.

While I have shown the preferred embodiments of the invention in the accompanying drawings, it will be understood, of course, that such embodiments may be changed and varied in details without departing from the invention as defined in the 55 appended claims.

I claim as my invention:

The improvements herein described comprising a sheet metal bracket provided with two parallel forwardly extending projections, an angle member pivoted at the free end, of one of its legs between said projections to swing horizontally, and means for yieldingly retaining said angle member in normal position comprising an integral 60 extension on the angle member bent at right angles past the pivotal connection, its free end curved outwardly, and a flat spring secured at one end to the bracket and extending between said projections and having its 65 free end curved outwardly to engage the free end of the projection on the angle member, as and for the purpose specified.

CHARLES W. KIRSCH.
